UNITED STATES PATENT OFFICE.

LOUIS C. BADER, OF CHICAGO, ILLINOIS, ASSIGNOR OF ONE-HALF TO MARTIN J. DETMER, OF CHICAGO, ILLINOIS.

GAS-BURNING HEATER.

1,269,517.

Specification of Letters Patent. Patented June 11, 1918.

Application filed September 11, 1916. Serial No. 119,588.

To all whom it may concern:

Be it known that I, LOUIS C. BADER, a citizen of the United States, and a resident of the city of Chicago, county of Cook, and State of Illinois, have invented certain new and useful Improvements in Gas-Burning Heaters, of which the following is a specification.

My invention relates to improvements in gas burning heaters designed for use particularly in connection with sad irons.

The object of this invention is the production of a device of the character mentioned in which the control of fuel to the burners of the heater and the lighting of the burners will be automatically controlled. A further object is the production of a heater which will be of durable and economical construction and efficient in use.

20 Other objects will appear hereinafter.

The invention consists in the combinations and arrangements of parts hereinafter described and claimed.

The invention will be best understood by reference to the accompanying drawings forming a part of this specification, and in which,

Figure 1 is a partially sectional plan view of a heater embodying the invention, 30 Fig. 2, is a vertical transverse section of the heater, and

Fig. 3, is an enlarged detail section taken through the contiguously positioned portions of the burners of the heater.

35 The preferred form of construction as illustrated in the drawings comprises a rectangular frame or body 1 in the top of which is formed a rectangular opening 2. Removably mounted in the opening 2 is a supporting plate 3 which is formed with two openings 4 of oval or elongated formation. Arranged in each opening 4 is a spider or supporting frame 5, the outwardly projecting fingers of the spiders 5 resting 45 upon the upper side of plate 3 for support.

Arranged directly below each of the openings 4 is a burner 6 of corresponding formation having fuel outlet openings at its upper side. The burners 6 are connected 50 through pipes 7 with a pipe 8 provided at the rear of frame 1, the pipe 8, in turn being adapted for connection with a hose or

supply pipe 9. The supply of the gas to the heater is controlled by a valve 10.

Interposed in each pipe 7 for the control 55 of the supply of gas therethrough, to the corresponding burner 6 is a valve 11 having an oscillatory operating arm or handle 12. Coöoperating with each of the valve arms 12 is a lever 13 which is fulcrumed intermediate its end as at 14 to a supporting member 15. The rearward end of each lever 13 is bent upwardly, the same being adapted to normally project above the corresponding supporting frame 5, so that upon the 60 placing of a sad iron upon the supporting frame, said end of the lever will be engaged and depressed in order to effect opening of the corresponding valve 11 as will be readily understood. The upper end of each 65 lever 13 is provided with an inclined plate 17 for engagement with the iron in sliding the same to position upon the supporting member, the provision of the inclined plate, as mentioned, facilitating engagement of 70 the iron with the end of the lever. Coöperating with each lever is a helical torsional spring 13' which is adapted to normally hold the lever in position as shown in Fig. 2, that is, with the rearward end thereof 75 projecting above the supporting member and consequently with the valve 11 in closed position.

Formed at the adjacent sides of the burner 6 are laterally projecting extensions 85 18 which terminate in close proximity with each other, said extensions being provided with fuel outlet slots 19 as clearly shown in Figs. 1 and 3.

In using the heater, the ironer is sup- 90 posed to use two irons, one being in use while the other is being heated. Gas will be supplied only to the burner above which the iron is arranged, the valve 11 of the other burner being normally held in closed 95 position, as above mentioned, through the influence of the spring 13' coöoperating with the corresponding lever 13. When it is desired to heat the second iron or the one which has been in use, it is only necessary 100 to place the same upon the unoccupied portion of the heater. When this is done the corresponding lever will be lowered to open the valve and the escaping gas will be

ignited or lighted by reason of the escaping of gas through the slot 19 of the burner, which extends into close proximity with the flame supported by the gas escaping from the 5 slot 19 of the other burner. The heated iron will then be removed, the corresponding burner being automatically extinguished as above mentioned. Thus it will be seen that but one burner will be in use at all times 10 during the ironing operation, the two burners being alternately in use as the irons are alternately used.

Through the employment of the slotted portions 18, the necessity of providing separate or additional means for supporting a 15 pilot light for each burner is done away with, since, with this arrangement, each burner serves as a pilot for the other, the location of the slots 19 in close proximity 20 with each other insuring instant lighting of the burners in the operation of the device. The slots 19 will be narrow or restricted so that only a small quantity of fuel will be 25 permitted to pass therethrough for the support of a comparatively low flame.

While I have illustrated and described the preferred form of construction for carrying my invention into effect, this is capable of variation and modification without 30 departing from the spirit of the invention. I, therefore, do not wish to be limited to the precise details of construction set forth, but desire to avail myself of such variations and modifications as come within the scope of 35 the appended claims.

Copies of this patent may be obtained for five cents each, by addressing the "Commissioner of Patents, Washington, D. C."

Having described my invention what I claim as new and desire to secure by Letters Patent is:

1. In a gas burning heater, the combination of a supporting frame; a plurality of burners arranged below said frame; valves coöperating with said burners to control the supply of gas thereto; contiguously positioned portions on said burners having adjacently positioned fuel outlet openings; 45 and a valve-operating member coöperating with each of said valves and normally projecting above said supporting frame, substantially as described.

2. In a gas burning heater, the combination of a supporting frame; a plurality of burners arranged below said frame; valves coöperating with said burners to control the supply of gas thereto; laterally projecting portions on said burners projecting from 55 the bodies thereof terminating in close proximity with each other and having adjacently positioned elongated comparatively narrow fuel outlet slots; and a valve-operating member coöperating with each of said valves and 60 normally projecting above said supporting frame, substantially as described.

In testimony whereof I have signed my name to this specification in the presence of two subscribing witnesses.

LOUIS C. BADER.
